BOTTLE CLOSURE

Charles J. Jesnig, Philadelphia, Pa., assignor of
one-half to Theodore G. Alteneder, Philadel-
phia, Pa.

Application July 27, 1935, Serial No. 33,450
Renewed October 28, 1938

7 Claims. (Cl. 215—21)

This invention relates to bottle closures, and particularly to closures of the so-called non-refillable type.

This application constitutes a continuation-in-part of application No. 756,021, filed December 5, 1934, and now abandoned.

So far as known in bottle closures as previously developed it has not been possible to provide a non-refillable device which was of such simplicity, economy, ruggedness and attractiveness in aspect as to have any appreciable commercial appeal. It has been found, moreover, that in most of the devices developed heretofore the bottles could be refilled, despite the alleged non-refillable nature thereof, by subjecting the bottles to the action of a vacuum, and by introducing substitute fluid to the evacuated bottle under a slight head.

It is among the objects of this invention; to improve the art of closures for bottles; to improve the art of bottles; to provide a closure for bottles or other receptacles which is possessed of simplicity, economy and ruggedness; to provide a bottle closure of a substantially non-refillable nature that will withstand the effects of evacuation by automatically closing the bottle against the entry of the supposed refilling fluid, or by preventing its pouring out after it has been illegitimately refilled; to provide a novel bottle arranged for association with a closure device; to provide a bottle closure with a valve which is closed in all positions other than pouring; to provide a valve in a bottle closure arranged for automatic closing if an attempt is made to refill the bottle; to provide a closure for bottles that will close automatically upon any attempt to evacuate the bottle and which functions substantially regardless of the amount of liquid in the bottle at the time; to improve the cap closure of bottles; to provide improved means to indicate the fact that a bottle has been opened; to provide a valve mechanism so arranged that with the valve seated through differential air pressures effective on the valve, the valve may be moved axially through appreciable distances without unseating the valve; to provide a bottle closure with sealing means arranged to prevent undesired rotation of the threaded closure cap; to provide a sealing valve structure in a preserving jar lid to enable evacuation for preserving purposes; to provide improved tops for mason jars and the like for preserving purposes; to improve closures for receptacles whereby tampering will be positively indicated; to provide a rupturable seal for a movable closure cap applicable

to both removable and non-removable caps; and many other objects and advantages will become more apparent as the description proceeds.

In the accompanying drawings;

Fig. 1 represents a fragmentary elevation of a bottle closed with a preferred form of closure,

Fig. 2 represents a fragmentary elevation of the end of the bottle neck with which the preferred form of closure is to be associated,

Fig. 3 represents a fragmentary section partially in elevation of the bottle neck and associated parts in closed position,

Fig. 4 represents an enlarged vertical section through the end of the bottle showing the relation of all of the working parts in closed non-pouring position,

Fig. 5 represents a similar sectional view through the bottle and closure with the parts in open and pouring relative position,

Fig. 6 represents a detached elevation of the movable valve element of the invention,

Fig. 7 represents a fragmentary diagrammatic section through one side of the valve device with its seat to show the normal gravitational seating of the valve,

Fig. 8 represents a similar diagrammatic view of the same elements as Fig. 7, with the valve shown seated under the influence of fluid pressure on the outer surface of the valve,

Fig. 9 represents a similar diagrammatic view of the same elements as Fig. 7, with the flexible margin of the valve shown seated by air or fluid pressure exerted upon the flexible valve element, while outward urging pressure, such as a surge of liquid within the bottle, has been effective to move the cylindrical valve element axially outwardly to a limited extent, short of actual unsealing of the flexible element,

Fig. 10 represents a fragmentary elevation of a closure cap having a form modified from that of Fig. 1, for sealing the closure to the bottle,

Fig. 11 represents a fragmentary transverse section through the bottle neck of Fig. 10, to illustrate the bendable or tongued sealing element and its relation to the thread groove of the bottle,

Figs. 12 and 13 represent respectively a similar fragmentary elevation and section of a modified form of sealing element for the closure and neck,

Figs. 14 and 15 represent respectively a similar fragmentary elevation and section of a further modified bottle and closure having a dimpled or depressed seal element,

Figs. 16 and 17 represent respectively a similar fragmentary elevation and section of a still further modified bottle and closure having cooperat-

ing sealing elements, but with the closure such as might be made detachable from the neck, if desired, and

Fig. 18 represents a side elevation partially in section of a jar closure, of the "Mason" jar type, having a valve element similar to that shown in the other figures.

Referring now to the preferred form of bottle closure, it will be understood, referring to Fig. 2, that there will be provided a neck 10, preferably having a bead 11, to retard manipulations on the end of the outer closure cap, and having the indented or grooved thread 12 or pair of diametrically spaced threads 12, disposed in the cylindrical portion 9 of the neck, and each terminating at its upper end in a shoulder 13. Preferably below the grooved thread, and above the bead 11, there is provided the pair of diametrically spaced peripheral grooves 14 having divergent angular relation to the helical thread grooves and of rather appreciable length. As will be explained the length of the transverse non-inclined recess 14 is each such as to permit a safety clearance on each end, for the subsequent indentation or forming of the sealing plug to be described. Preferably each sealing groove 14 has a sharp upper and right hand margin where it is formed in the glass of the neck. Above the upper termination 13 of the helical grooves, on the outside of the neck, the peripheral annular groove 15 is formed. This groove serves two functions, one, to be described, and the other to form a break in continuity between the outer diameter of the neck portion 9 having the thread grooves formed in it, and the slightly reduced rim portion 16. The difference in the respective diameters is substantially the thickness of the wall of the inner cap to be described. The rim portion ends in the rim or lip 17 against which the sealing element, to be described, is axially engaged under such pressure as to close and seal the bottle. Internally the neck emerges from the bottle with a passage surface 17 which merges into the annular internal shoulder 18, and then expands to form the enlarged relatively short internal substantially cylindrical surface 8 merging into the outwardly flaring or tapering opening 20 extending to the rim.

It will be understood that the upper surface of the shoulder 18 is substantially in line with the outer shoulder 19 formed by the junction of rim portion 16 and groove 15, or nearly so, and is a step in the manufacturing process of the bottle that is very important. The provision of the annular groove 15 excellently serves the purpose of forcing or squeezing the molten glass inwardly during the molding to form the internal shoulder 18. It will be understood that while a continuous annular shoulder 18 is contemplated and is preferred, yet it may be interrupted so as to comprise in effect a spider or other series or plurality of spaced supporting lugs (not shown) if desired. It will be understood that the inner neck surface 20 may be substantially cylindrical from the shoulder 18 to the rim 17, but preferably it has a greater or less degree of flare or outward taper in accordance with requirements, both as to the necessary strength of the bottle rim, pouring speed desired from the neck, and so on, and is usually a mergence of a cylindrical extent 8 adjacent to the shoulder 18, turning into the outwardly flared or tapered portion 20 just above the frictional washer of the valve insert to be described.

The valve insert or assembly is well shown in

Figs. 4 and 5 and is disposed as a unit which substantially comprises a cylindrical sleeve valve device having lateral ports, a valve seat and valve guide with reference to which the sleeve valve has axial movement, and a flexible washer device mounted on the cylindrical portion having a marginal portion in position to flex axially in both directions and to overlie the valve seat. Refinements and details will become more apparent as the description proceeds.

Referring to Fig. 4 a valve guide housing comprising a short tubular shank portion 21 defining a valve opening is provided merging into a transverse flange or seat 22, which latter in turn merges into the short cylindrical sleeve 23 the axis of which is substantially concentric with the axis of the guide housing 21. The valve seat 22 may under certain conditions comprise a mere plane substantially perpendicular to the axis of the guide housing 21, but it is preferred that it have an annular ridge, crest or peak portion 24 raised out of the plane of the seat 22, and which peak is transversely curved and is preferably arcuate in cross section and is disposed so that the guide surface internally of the guide housing 21 merges into the peaked seat 24 as a substantial tangent thereto. It will be clear that the arrangement described and as shown, provides an apex or annular peak on the valve seat, which is laterally spaced from the guide surface of housing 21. This spacing is of importance, as is the generally curved nature of the peaked portion of the seat, for reasons to be described.

It will be obvious that with satisfactory molding conditions, a substantial reproduction of the guide housing 21, lateral valve seat 22 and short larger cylindrical sleeve 23 could be formed in the neck of the bottle, from the inner surface 17, shoulder 18, suitably formed, and tapering surface 20. Thus, under certain circumstances, a cheaper product could be provided by which the parts, just described, could be obviated as a separate insert as shown in Fig. 18. However, owing to the uncertainties of molding, among other disadvantages, the insert valve assembly as thus far described is preferred.

The guide housing and valve seat described as a separate unit, may be completed by the provision of a closure cap device 25 having an upper plane closure surface 26 preferably closed throughout its entire area, having the peripheral ports 27 just beneath the upper transverse closed end, and having an enlarged off-set cylindrical sleeve 28, arranged to frictionally slidingly embrace the cylindrical sleeve 23 of the valve housing and to remain locked therewith through friction or any other desired form of lock. The closure device is not applied until after the movable valve element to be described is first installed in the assembly. When the closure is rigidly engaged upon the housing it forms a cage or insert device which can be manipulated and installed in the neck as a unit. The unit is completed by the provision of a metallic disc or plate washer 30 having a tight but sliding fit over the reduced cylindrical valve guide 21, and of such diameter as to insure supporting engagement with the glass shoulder 18 of the bottle neck, and which washer engages the lower surface of a resilient washer 31 of such internal diameter as to frictionally engage and seal the external surface of the valve guide 21, and of such external diameter as to frictionally engage and seal the internal surface 8 of the bottle neck 10. The sealing washer 31 is engaged axially between the disc 75

washer 30 and the lower surface of the valve seat portion 22, and, preferably, the lower edge of the enlarged cylindrical sleeve 28. With the valve housing assembly in operative position in the bottle neck in engagement with the internal surface of the neck at 8, and engaging shoulder 18, it will be clear that there is provision for a slight axial yielding of the assembly to facilitate seating of the outer bottle closure to be described to maintain its seal, but this yielding is sharply limited owing to the fact that the resilient washer 31 has such restricted area into which to "flow" under axial pressure. It can yield slightly to such axial pressure to increase its transverse or lateral frictional engagement with the surfaces it is supposed to seal (the bottle neck and the valve housing), but it cannot, preferably, be susceptible to continued inward axial movement thereafter.

The valve device itself, that is the movable element, comprises a substantially cylindrical tubular plunger or valve shank 32 of such external diameter as to have easy sliding fit within the valve guide 21 (or the internal bottle surface 17 if the shoulder 18 is used as the valve seat itself). The plunger preferably has one end closed as at 33 and is provided with an axial separate or integral rivet or the like 34, upon the outer diameter of which the flexible resilient washer or flexible flange 35 is mounted, overlying the outer surface of the closed end, and which is held in place by a metallic plate washer 36 seated upon the rivet and of substantially the same outer diameter as and forming in effect an extension of the plunger 32. The end of the rivet 34 is swaged or otherwise upset as at 37 to force the plate washer 36 against the resilient washer. Obviously the plunger or piston valve device can be formed in any other desired manner, as the only essential is that the flexible washer 35, which is preferably quite thin, have a peripheral marginal portion 38 which is capable of free flexing in both axial directions. The plunger has peripheral ports 40 through which, as shown in Fig. 5, the liquid in the container can pass when the ports 40 in the movable device are in substantial registration with fixed ports 21 in the cage in the normal proper operation of the bottle assembly.

When the plunger or movable valve device is disposed in the cage assembly in sliding relation to the housing, the normal gravitational functioning that ensues is the downward sliding of the movable elements until the ports 40 are below the level of the valve seat so that egress (or ingress) of fluids through the ports 40 is precluded by the closing of the ports by the cylindrical housing 21. Such relative liquid movement is also prevented by the fact that the marginal flexible portion 38 of the washer 35 engages axially upon the peak 24 of the seat 22 of the valve, as the only support of the movable sleeve or plunger. As shown in Fig. 4, and in the fragmentary diagrammatic showing of Fig. 7, the axially flexible margin 38 of the sealing washer 35 engages the peak 24 in appreciably spaced relation to the outer wall surface of the movable plunger 32, and this space or clearance is preferably as wide as is reasonably convenient to provide, for reasons to be described, and in the first instance upholds the plunger against gravity by the resistance of the flexible margin to shear and compression strains, and to its inherent resistance to flexing. Obviously with a thin washer especially adapted for flexing of its marginal portion, it has relatively small rigidity so that the actual position assumed by the parts is not really as

shown in Figs. 1 and 7, but somewhat between the showings of Figs. 7 and 8. In Fig. 8 the plunger is shown in an extreme inward position in which the flexible washer still prevents the plunger from falling inwardly, through resistance 5 of the washer to shearing strains, and through the fact that the outer diameter of the top plate 36 is close enough to that of the cylinder 32 that the marginal portion 38 of the washer cannot be bent into a cylinder, the outer diameter of which 10 is substantially the same as that of plunger 32. Owing to the lightness of the parts used in the preferred form the normal gravitational aspect of the assembly will be less extreme than as shown in Fig. 8. 15

It should be noted that the inner substantially cylindrical surface of the entire cage assembly has just such clearance from the outer periphery of the marginal flexible portion as to be possessed of a sort of piston and cylinder relation, 20 and especially so below the cage ports 21, for reasons to be explained.

Before describing the functional benefits of the valve construction shown, the remainder of the cooperating parts of the device should perhaps be described. Referring to Fig. 4, it will be observed that the closure device per se comprises an inner cap 41 comprising a substantially cylindrical sleeve portion 42 arranged for a sliding but tight or snug fit with the reduced rim 30 portion 16 of the neck 10, and which is disposed for axial movement only, in the preferred form. This may be enhanced by forcing the thin cylinder 42 to conform to a slightly oval neck portion 16. The sleeve 42 merges into a transverse inwardly directed perpendicular plane portion 43, which latter merges in turn, by the axial inward extension 44, into the reduced cylindrical spout portion 45. The inner cap may be protected against efforts to pry into the interior with wires 40 and the like, by the mesh or reticulated metallic screen 46, preferably having the outer flange 47, and the annular recessed portion 48 to fit into the recessed end formed by the annular inward extension 44, and is cemented or otherwise anchored within the cap. The sealing gasket 50 of any desired material and of any desirable thickness is cemented or glued or otherwise secured to extend laterally outwardly to sealing engagement with the inner surface of the cylinder 42 or flange 50 47 of the mesh material, and inwardly to the aperture 51 forming a surface that engages in part at least the axial inward extension 44 or the mesh in contact therewith. The axial inward extension is preferably provided to prevent the entry of fluid, possibly containing solvents such as alcohol, beneath the sealing gasket, to permit its detachment. It also serves to prevent the entry of fluids into the exposed cut portions of the gasket exposed at the aperture 51, to a large extent, and obviously it can have such size and proportions as best to serve the desired ends. The function of the spout in pouring liquids from the bottle will be apparent from Fig. 5. 55

The inner cap is arranged for axial movement only, in the preferred form, by means of a rotatable outer cap 52, having sliding engagement with the outer surface of the cylinder 42 of the inner cap, and with the outer surface of the groove threaded portion of the bottle. The outer cap comprises a cylinder 53 housing the inner cap 41 and the grooved threads, having a knurled portion 54 if desired to facilitate rotation by manual grip, and has a tapering end portion 55 the wide outer portion of which engages the 75

upper outer surface of the flange or transverse plane portion of the inner cap and has a reduced smaller end embracing slidably the end of the spout 45, and secured thereto by the spun over or swaged end 56 of the spout. It will be observed that the outer cap can rotate in either direction relative to the inner cap when the latter is frictionally engaging the bottle, but that any axial movement of the outer cap forces the inner cap, to move axially with it, and thus to move between sealing and unsealing position.

Obviously the outer cap may have threads formed in it to engage over external threads upon the bottle neck, but for several reasons the threads are preferred to be grooves disposed in the neck of the bottle, as it thus furnishes a solid corner or shoulder of glass for a purpose to be described, and enables the maintenance of a smooth exterior of the outer cap such that its embellishment and decoration as desired is facilitated and the visual aspect improved. To both thread the outer cap to the bottle and also secure it in place when threaded, it is but necessary to indent a lug 57, or a pair of such lugs, into the respective thread grooves, by drawing the metal so that it cannot be crowded back into its original place in the periphery of the cylinder, and the cap is threaded to the bottle and cannot be removed because the lug 57 engages a positive abutment 13 comprised of the shoulder 13 at the upper end of the thread groove in the bottle neck. The outer cap being thus lockable onto the bottle, it will be clear that, with the bottle filled with liquid, and the valve insert assembly as shown mounted within the bottle neck, then screwing the cap downwardly will force the inner cap axially to force the gasket 50 into sealing engagement with both the central valve cage assembly and the rim 17 of the bottle. A reversed motion of the outer cap will apply pressure axially outwardly of the spout 45 effective upon the swaging 56 to unseat the inner cap and gasket, to the position shown in Fig. 5, to permit normal pouring from the bottle. The pouring will be preceded by the unseating of the valve plunger, the lifting of the flexible washer from its valve seat, the moving of the ports 40 above the valve seat, and the free pouring of the liquid in the path of the arrows of Fig. 5, from the pouring spout 45. When pouring has stopped and the bottle has been set upon its base, the small amount of liquid contained in the space between the rim and the valve assembly will be trapped therein, usually, to maintain a liquid seal upon the flexible washer as the latter gravitationally closes.

Referring to Fig. 18, there is disclosed the threaded top 80 of a "Mason" jar or the like usually made of a single piece of metal having the more or less plane top 81, and threaded peripheral flange 82, and in use on a threaded glass jar or the like (not shown) having a gasket 83 to engage the upper rim of the jar to seal the joint. The successful use of such jars and tops for preserving purposes involves the exhaustion of air from the containers. While it is recognized that there have been other attempts to provide forms of valves in such jar tops, yet these have been of great cost, and of dubious merit, owing to their inability to maintain a seal even under quiet conditions, much less in the presence of abrupt manipulations of the containers, such as might be incident, for instance, to dropping a crate thereof from a truck body.

To establish and preserve a seal at a low cost 75 the top 81 (Fig. 18) of the jar cover 80, is provided

with the axially drawn valve seat structure comprising the short cylindrical guide 84, open at the top and bottom in a guide or valve opening, merging into the valve seat 85, the annular peak of which is outwardly or radially spaced from the internal guide surface of the guide 84, and which valve seat merges into the enlarged cylindrical wall 86, forming a valve chamber, as a continuation of the top wall 81. Obviously instead of the integral drawn member shown, the valve seat and guide could be a separate element, soldered or otherwise secured to the jar top.

The valve element proper, of the jar top of Fig. 18, comprises a cylindrical element or shank 87, having preferably a loose sliding engagement in the guiding sleeve 84, and closed at the upper end by a wall 88, and swaged or upset at its lower end as at 90 to prevent undesired outward movement of the valve in the guide housing. The valve element 87 has a reduced port 91 to permit desired restricted air movement for venting gas pressure from within the container to the space between the shank and the guide surface and thus to the contact line between the annular valve seat crest and the superposed flexible flange, and carries a washer or flexible flange 35 having the flexible marginal or flange portions 38, functioning relative to the valve seat exactly as the flexible washer of the bottles function, as has been and will be described. The flexible washer is secured firmly in place by a dished or otherwise shaped guard 92 having an inner part 93, of the same diameter, substantially, as, and forming in effect an extension of, the valve cylinder 87, and a raised outer ring 94 forming a housing 35 and prying element having relatively small clearance from the walls 86 forming the valve housing and held in place as by a rivet 95. It will be clear that after the jars are filled with the foodstuffs or the like, and the lids or tops are screwed on, then the jars may be placed in boiling water to sterilize the contents and cause the entrapped air to expand with a consequent increase in pressure, which will unseat the valve and flexible washer or flange to permit escape of air through port 91. Obviously, as will be explained in connection with the bottles and which also maintains as to Fig. 18, any return movement of fluid, whether liquid or gas will cause the sudden snapping shut of the valve. Alternatively, a suction device may be applied to exhaust the air in the jar, and to seal the valve automatically upon breaking the suction and admitting atmospheric pressure to the outside of the jar valve. The valve may be pried open by a knife, or the like, inserted under the edge of the guard 92. Any other sort of device desired can be used to break the seal and admit air through the valve when desired, as for instance by forming a ring or head on rivet 95, which can be pulled to insure a direct axial pull on the valve, in place of the eccentric thrust of the pry under guard 92.

It will be apparent that with the matter thus far disclosed there is no means discussed for indicating the fact that a bottle has once been opened. Furthermore it will be clear that the threaded assembly disclosed may be subjected to jarring and the like in transit that, in sporadic cases, may cause slight rotative movement such as to permit seepage from the bottle. To protect against this and to provide an improved seal and indicator of tampering with the bottle is an important object of this invention.

It will be understood in the preferred form of the invention, the filled bottle is provided with 75

5 a valve insert, which is substantially seated on its shoulder 18, and that the compound cap of the invention, comprising the coupled inner and outer cap members, is pushed on axially with such pressure as may be desired, and with the gasket 50 in sealing engagement with both the compressible axial insert and the rim 17, the thread lugs 57 are simultaneously formed on diametrically opposite sides of the outer cap and pushed 10 and drawn inwardly to lie in and be in mesh with the indented thread or threads 12 of the bottle at some point between its end or its respective ends, if the threads are plural. At the same time, preferably, that the tool moves forward to force 15 lugs or abutments 57 out of the peripheral extent of the outer cap, a tool (not shown) moves forward to force lines of scoring 60 (Fig. 4) about an indented sealing button or tongue 61, bent inwardly out of the peripheral extent of the outer 20 cap cylinder to lie in intimate frictional relation with the cooperating surface of the peripheral external slot 14, which is parallel to the plane of rim 17, and of greater length, preferably, than the button 61, so that exact lining up of the button between narrow limits of shoulders is obviated.

It is to be observed that the peripheral external slot or groove 14, has a divergent angular relation to the helical thread groove 12, so that with the slightest effort to rotate the outer cap the button 61 is given a downward pressure from the upper shoulder of the groove 14, such as to tear the button 61 loose from its weakened connection with the outer cap 52 and it will be forced outwardly through its scored aperture to a point of complete severance from the cylinder 52 of the outer cap. It will be observed that button 61 by reason of its being forced into indented seated relation in arcuate slot 14 has been extruded or 40 drawn or caused to flow so that it is hardened somewhat and made relatively brittle to serve two desired ends. First is to prevent its being unlawfully pulled out into the original arcuate extent of the bottle with intent to deceive observers by 45 subsequently being indented again pursuant to efforts to refill the bottles. This latter of course is only contemplated if the cap assembly shown should be used without the valve insert combination such as is contemplated in certain types of 50 installations. Secondly, the indentation, or drawn or dimpled button 61, is a substantial continuation, an integral portion, of the closure cap proper and can be instantly observed to be intact or to be missing and the latter serves visual 55 notice that the cap has been moved to pouring position. The advantage of the drawn indented button, as shown, is that it assists in preventing manipulations by external tools and is more easily and quickly observed. It will be understood that 60 rotation of the cap to open the bottle for pouring purposes will be accompanied by movement of the lugs 57 in grooves 12, until they abut the respective thread shoulders 13 when the upward movement of the closure cap terminates. Obviously at this time the rotation of the outer cap has imparted axial movement to the inner cap by means of the wedged flange 56 so that the bottle becomes unsealed.

65 Referring to Figs. 10 and 11 a modification of the sealing device is indicated in that with all other portions of the invention the same, a tongue 62 is struck inwardly from the arcuate extent of the closure on a line of scoring or weakening 63, preferably of such profile as to fit 70 snugly in the bottom of groove 12 and to be bent

5 into abutting engagement with shoulder 13 in the end of groove 12. In this case there is left an aperture 64 through which the observer can note the presence or absence of tongue 62 in its abutting disposition. With the tongue or sealing lug 10 fitting snugly in the end of the threaded groove it will manifestly be very difficult to manipulate same by tools supplied externally through the aperture 64. The tongue 62 is preferably so disposed as to tenuousness of connecting link with the main body of the cylinder 52 as to be broken and moved out of the aperture 64 upon the slightest attempt to bend it back into any position such as to permit shoulder 13 to slide past it in the rotative opening of the bottle.

15 In Figs. 12 and 13 a further slight modification is shown in that the tongue 65 is struck in to leave aperture 66, with the tongue attached by weakened connections with cylinder 52 and lying in substantial parallelism with the thread groove 12 20 so that the edge of tongue 65 is in position to be engaged by shoulder 13 so that relative movement of tongue and shoulder enhances the shearing function to force the tongue 65 loose through shearing rather than mere bending as in the case 25 of the form shown in Figs. 10 and 11.

30 In Figs. 14 and 15 there is provided an indented, drawn, dimpled seal 68 having a weakened line of scoring 70 and arranged to be indented to substantial abutment with shoulder 13 35 of the thread groove and arranged to be forced outwardly to leave an aperture when the seal has been broken, but arranged to show a continuation of the metal housing if the seal has not been broken. It is believed the operation of this 35 will be understood.

40 In Figs. 16 and 17 there is disclosed a further modification by which the benefits of a portion of the invention can be secured with a cap which is removable from the bottle. As shown the bottle 40 itself has a helical indented or other sort of groove or thread 71 which has no upper termination below the rim. In spaced relation to it, at its lower end, a recess 72 is provided. The cap 73 has either threads cast in it to mesh with 45 threads 71 or has suitable lugs as in the other forms described in this application so as to be axially removable by an unscrewing function. The cap 73 has a scored and weakened indented tongue 74 arranged to abut shoulder 75 formed at 50 one edge of recess 72. It will be clear that the cap 73 may be provided with the sealing device shown or with any of those already described in connection with the preferred embodiment of the invention so that the cap 73 cannot be unscrewed 55 for removal without first breaking away the sealing tongue 74. There will obviously be many other variations and modifications which will occur to those skilled in the art by which the principles of the sealing devices, thus far described, 60 may be utilized, and all such are to be construed as within the scope of the instant invention.

65 It will be understood that with the complete assembled invention as disclosed, the purchaser has a bottle provided with a number of safeguards, which contribute to providing an outer closure of simplicity of design which cannot jar loose on its threads in transit because of the provision of a sealing medium preventing either axial or rotative movements or both, and which 70 is doubly sealed in the proper upright position by the fact that plunger 32 hangs down in guide 21 to close its ports 40, which is also accompanied by the seating about the entire periphery of the flexible marginal portion 38 of washer 35 on the 75

seat peak 24 and by the engagement of the sealing gasket 50 with the rim 17 of the bottle and the closure top element 26 of the insert. Unscrewing the outer cap, breaking the seal out to permit rotation, by rotation of the cap or by providing supplemental manual tearing out tabs or the like (not shown) enables axial movement of the cap closure so that gasket 50 is moved axially away from its seat on rim 17 and cage end 26 to expose a passage through cage ports 27, flaring passage 76, between the outwardly flared wall surface 20 of the bottle and the inwardly tapered wall surface defined by the retracted upper end 26 of the cage closure relative to the enlarged embracing cylindrical portion 28 thereof and which passage 76 is in communication with the pouring spout 45. At this juncture, however, the gravity valve element or plunger 32 remains in its closed position. Tilting the bottle permits plunger element 32 to move axially in the guide 21 to move flexible washer 38 off seat 22 and also to bring its ports 40 into position to register with the ports 27, and channel 76 to permit the fluids in the bottle 25 to pass out of the bottle. Termination of the pouring and returning of the bottle to upright position marks inward and downward movement of the plunger 32 to close both the sliding and poppet valves associated therewith. The few 30 drops contained in passage 76 and spout 45 will be trapped against reentry. Owing to the tight sliding axial engagement of the inner cap 41 with the reduced cylindrical end 16 of the bottle, there will be practically no seepage or leakage 35 of the fluid in the pouring channels at the time the pouring stops so that it cannot run down into and about the threads to leakage over the neck of the bottle as is common to most of the prior art devices, so far as known.

40 Any attempt to pour liquids into the bottle through spout 45 will inevitably result in failure, because of the fact that the valve 32 remains closed. There has developed a technique of bootlegging, the essential ingredient of which is the 45 subjecting of the bottle to the action of a vacuum during or following the existence of which fluid may be caused to move upwardly through the inverted bottle neck into the bottle. Great success has been attained with filling bottles according to this procedure, according to the prior art, and it is a feature of this invention to preclude this mode of refilling the bottle, or at least so 50 substantially to minimize it as to render it impossible upon any commercial basis.

55 Referring to Figs. 4, 7, 8 and 9, it will be observed that the plunger 32 and flexible washer 38 constitute a piston movable in the cylinder of the upper cage member so that when the air pressure effective upon the outer upper end of this 60 piston is greater than the air pressure on the inner upper end of the piston, the piston snaps shut. Regardless of the scientific reason for the activity it is a well established fact that pursuant to an evacuation of the bottle by subjecting both sides of the valve to less than atmospheric pressure while the bottle is held upside down so that the valve can fall open, this opening is 65 terminated with a snap when it is sought to restore the bottle to normal atmospheric conditions 70 externally. It will be understood that for all practical purposes the existence of differential air pressure on opposite sides of flexible valve 38, if the pressure externally is the greater, the valve will be held tightly closed by air pressure effective over the entire outer area of the piston and

particularly effective upon the flexible margin 38 to cause it to tightly engage and seal itself upon the peak 24 of seat 22. As shown in Fig. 7 the gravitational seating of the flexible margin 38 may be at a point spaced appreciably from the guiding surface of guide 21. When there is an appreciable condition of vacuum within the bottle, the greater external atmospheric pressure may cause the valve to be pulled inwardly so that the flexible margin 38 rolls around the peak 24 to engage closer to the guiding surface 21. In this relation, by the way, the thin flexible washer 38 holds the plunger 32 into the bottle by squeezing of washer 38 between the outer margin of plate washer 36, and the valve seat 22 as shown in Fig. 8. It may have happened that some portion of liquid has been successfully introduced into the bottle at the time that the vacuum condition became effective to exert differential pressure on the valve and the bottle 20 may even have been filled before the valve snapped shut.

It will be clear that with the bottle half filled, for instance, violent oscillations of the bottle could cause pounding surges of liquid within the bottle to be incident upon the inner face of the closed end 33 of plunger 32 to develop violent unseating urges of the piston tending to force washer 35 from the seat 22. This impact factor would probably be of considerable concern in 30 any other type of valve closure than the one disclosed. Owing to the air pressure effective on the outer face of the piston valve forcing the flexible washer into sealing engagement with the valve seat and owing to the fact that the peak 35 of the valve seat is considerably spaced relative to the cylindrical guide wall 21, there is thereby provided means whereby considerable axial movement of the cylindrical plunger 32 in both directions can occur while the air pressure is effective 40 to force the thin flexible washer marginal portion 38 against the rounded peak 24. In other words the outward surge of liquid is driving against the excess air pressure trying to force it inwardly to the position shown in Fig. 8. 45 Therefore the first outward impulse is marked by absorption of the energy by the excess air pressure against which it must function. Continued application of the surge of fluid energy after the valve has been pushed outwardly to 50 the position, shown for instance in Fig. 7, is marked by the continued flexing of the marginal portion 38 while maintaining sealing engagement with some portion of the peak 24, as shown in Fig. 9. There seems to be a sort of rolling 55 action that occurs when there is a vacuum in the bottle, and the plunger valve is subjected to outward urges, the rolling beginning with the marginal portion 38 in contact with the peak 24 rather close to the guide surface of guide 21, as 60 shown in Fig. 8, rolling outwardly radially to the position shown in Fig. 7, to an extreme outward roll of the contact area, as shown in Fig. 9. In other words when the valve in the valve insert has once snapped shut because of atmospheric 65 pressure on one side of the valve with vacuum or smaller pressure inside of the bottle, it remains permanently sealed against the egress of any of the contents of the bottle.

It will be understood that all resilient washers, 70 gaskets, flanges and the like, will be made of suitable materials that are resistant to adverse chemical reactions from the fluids in the containers. There is an alcohol-proof rubber now available from which it is preferred to manu- 75

facture the flexible washer 35 and the gasket 31.

The features and advantages of the invention are thought to be clear.

I claim:

5. 1. In receptacles, in combination, means having an integral valve seat having an annular crest and a substantially concentric valve guide spaced from the crest, a cylindrical valve element in the guide and having a movable portion 10 extending beyond the valve seat end thereof, a flange operatively associated with the said portion of the cylinder and having a margin capable of flexing in both axial directions and of such diameter as to overlie said crest and to sealingly 15 engage said crest to seal the space between the crest and the valve element during various conditions of flexing incident to movement of said portion.
2. In receptacles, a means having an integral 20 valve seat and a substantially concentric valve guide, a cylindrical valve element slideable in the guide and having a port, a washer operatively associated with the cylinder and having a margin arranged for flexing in both axial directions overlying said seat, said seat having an annular peak radially appreciably spaced from the guide to establish clearance for such marginal flexing.
3. In receptacles, means having an integral 25 valve seat and a substantially concentric valve guide, a cylindrical valve element slideable in the guide, a flange operatively associated with the cylinder and having a margin arranged for flexing in both axial directions overlying said seat, means anchoring said flange to the valve element to prevent undesired flexing of said margin away from said seat to maintain sealing engagement therewith, said seat having an annular peak radially appreciably spaced from the guide to establish clearance for such marginal flexing.
4. In receptacles, a means having an integral 30 valve seat and a substantially concentric valve guide, a cylindrical valve element slideable in the guide and having a port, a washer operatively associated with the cylinder and having a margin arranged for flexing in both axial directions overlying said seat, and means overlying said washer to prevent undesired flexing of said margin away from said seat to maintain sealing engagement therewith, said last mentioned means

comprising a washer having a dished profile with the smaller portion of substantially the same diameter as the cylindrical element and in engagement with the washer, and with the larger portion overlying the seat in spaced relation to 5 said washer.

5. In closures for receptacles, a removable closure having a wall, a recessed valve seat having a substantially concentric guide sleeve disposed in said wall, a valve cylinder slideable in said sleeve and having a portion disposed to abut the end of said sleeve in one axial position, a washer mounted on said cylinder having a flexible margin in position to engage said seat in another axial position of said cylinder, means forming 10 a substantial extension of said cylinder on the opposite side of said washer to prevent the flexible margin from flexing to a point permitting the cylinder to pass out of the lower end of said sleeve and undercut means facilitating prying 15 the valve outwardly relative to said wall.

6. In closures, means defining a substantially cylindrical valve guide, a valve seat disposed concentrically of the valve guide having an annular peak spaced from the valve guide, the peak 20 merging into the guide with a curved surface, valve means slideable in said guide, a washer carried by said valve means and comprising a relatively thin flexible margin overlying said peak and curved portion and so arranged that the 25 washer margin can flex relative to said valve means toward and away from said curved surface while maintaining contact with said peak.

7. A bottle closure comprising a bottle neck having an internal shoulder and an annular rim, 30 a valve assembly comprising a cage and a cylindrical shank disposed in said neck in engagement with said shoulder, said cage having slots and a closed end, a valve element slideable in said shank and having ports arranged to register 35 with said slots when the valve is open, a flexible washer carried by said cylinder in position to engage a portion of said cage and to serve as an automatic closure device when moving fluid is incident upon the upper surface of said washer, 40 and means removably engaging the cage and said rim to temporarily seal said neck.

CHARLES J. JESNIG.
